(57) **CLAIM**

The ornamental design for a turntable for a condiment storage and dispensing carousel, as shown and described.

DESCRIPTION

FIG. 1 is a perspective view of a turntable for a condiment storage and dispensing carousel, the turntable being symmetrical about its central vertical axis, and the bottom surface of the turntable being unadorned;

FIG. 2 is a top plan view of the turntable shown in FIG. 1; and,

FIG. 3 is a side elevation view of the turntable shown in FIGS. 1 and 2.
